PIETRO TORELLO, OF NEW HAVEN, CONNECTICUT.

MARKING DEVICE.

1,073,592.

Specification of Letters Patent. Patented Sept. 23, 1913.

Application filed October 5, 1912. Serial No. 724,100.

To all whom it may concern:

Be it known that I, FILIBERTO CONTENTI, a subject of Victor Immanuel III, King of Italy, residing at New Haven, in the county 5 of New Haven and State of Connecticut, have invented certain new and useful Improvements in Marking Devices, of which the following is a specification, reference being had therein to the accompanying drawings.

My invention relates to a new and improved marking device, having particular reference to a tool for tailors to hold their marking chalk and the marking wheel, for 15 outlining patterns, having for its object, among other things, the arrangement of the parts of such a device that the chalk and wheel may be securely held in variously adjusted positions, all so designed that they 20 may be manufactured at the minimum cost.

To these, and other ends, my invention consists in the marking device, having certain details of construction and combination of parts, as will be hereinafter described and 25 more particularly pointed out in the claims.

Referring to the drawings, in which like numerals of reference designate like parts in the several figures; Figure 1 is a view of my improved device; and Fig. 2 is an enlarged 30 side view thereof, with the side plates and marking wheel partly in section.

In the practice of my invention, I provide two side plates 1—1, which are substantially triangular in shape, and having a slot 2 therethrough near one corner of the triangle, through which projects the pin 3, upon 35 which is rotatably mounted the toothed marking wheel 4. The pin 3 is reduced in diameter at both ends where it passes 40 through said plates and upon one end is a washer 5 and a nut 6 is threaded upon the other end, both of which coöperate to hold the side plates together at one point, and the pin in its various relative positions within 45 the slots 2, whereby the periphery of the wheel 4 may project beyond the said side plates or be entirely covered thereby, as desired. The plates are joined at the opposite 50 end by the thumb screws 8, which pass freely through one of the plates and are threaded into the other. The rotation of these screws in one direction draws the plates together and their rotation in the opposite direction allows them to spread apart,

the metal having sufficient spring for this 55 purpose.

Held between the side plates and the screws is a block of marking chalk, designated by the numeral 7. By holding the chalk in this manner, it is always dry and 60 not subject to the action of the moisture of the hand, as when held between the fingers, and it permits the arrangement of the chalk block so that only sufficient projects beyond the side plates to present a marking surface, 65 thereby insuring the consumption of substantially the entire piece.

The marking wheel 4 may be operated with the wheel in contact with the cloth in substantially the position shown by the 70 dotted lines A—B of Fig. 1, or with the edges of the side plates resting upon the cloth and steadyng the wheel, as shown by line C—D in the same figure.

Much care and experience is required to 75 mark a garment with the wheel and holder in the first above described position, as there is nothing to steady or guide the hand, but if the side plates are allowed to rest upon the cloth, as in the second above described 80 position, they steady the wheel and it is a comparatively simple operation to properly guide the marking wheel.

Of course, the shape of the device and other minor details of my invention may be 85 varied considerably, and I therefore do not limit myself to the exact construction herein shown and described, but claim all that falls fairly within the spirit and scope of my invention. 90

Having described my invention, what I 95 claim as new and desire to secure by Letters Patent, is:—

1. In a device of the character described, the combination with two side plates; of a 95 pintle connecting the same at one end; a marking wheel mounted upon said pintle between said side plates and rotatable upon said pintle; a block for holding said plates apart opposite to said pintle; and screws 100 passing through said plates adjacent to said block arranged so as to draw said plates together and grip said block without bearing against the sides of the marking wheel and prevent its rotation. 105

2. In a device of the character described, the combination with the side plates, substantially triangular in form; of a marking

wheel rotatably mounted between said plates at one corner of the triangle; a separable block for holding said plates apart opposite said marking wheel; and screws at the opposite corners of said triangle passing freely through one of said side plates and threaded into the other of said side plates and arranged to draw said plates together and grip said block without interfering with the rotation of said marking wheel.

3. In a device of the character described, the combination with two side plates, having substantially parallel slots therethrough; of a pin connecting said side plates and passing through said slots; a nut threaded on said pin; a marking wheel upon said pin between said plates; and screws passing freely through one of said plates and threaded into the other of said plates, whereby each of said plates is held in such proper relation to the other that the said slots are always in register with each other.

4. In a device of the character described,

the combination with companion side plates of substantially the same form and shape, having slots therethrough; of a pin connecting said side plates, the ends thereof being of reduced diameter and passing through said slots; a marking wheel upon said pin between said plates; means connected with one end of said pin to prevent the accidental disengagement thereof from the side plates but permitting its movement within the slot therein; a nut threaded upon the opposite end of said pin; and screws passing through said side plates at the end thereof opposite to said pin, whereby said plates are held in such proper relation to each other that each of said slots is always in register with the other.

In testimony whereof I affix my signature in presence of two witnesses.

FILIBERTO CONTENTI.
